UNITED STATES PATENT OFFICE.

JAMES METCALFE AND JAMES CROXON METCALFE, OF MARPLE, AND RICHARD DAVID METCALFE, OF ROMILEY, ENGLAND.

INJECTOR.

1,329,465.

Specification of Letters Patent.

Patented Feb. 3, 1920.

Application filed July 8, 1919. Serial No. 309,310.

To all whom it may concern:

Be it known that we, JAMES METCALFE and JAMES CROXON METCALFE, both of Sheen Bank, Marple, in the county of Chester, England, and RICHARD DAVID METCALFE, of the Mount, Romiley, in the county of Chester, England, subjects of the King of Great Britain and Ireland, have invented certain new and useful Improvements in Injectors, 10 of which the following is a specification.

This invention relates to steam injectors and has for its object to provide improved means for controlling the overflow from the injector when the latter is starting.

15 With injectors dealing with hot feed water and high pressure steam, difficulty is experienced in obtaining a sufficiently free overflow at starting to permit of the quick establishment of a proper condensed steam jet in the combining nozzle having the necessary velocity to deliver into the boiler or vessel being fed. In our prior Patents Nos. 905206 and 1,194,207, we have proposed to divide the overflow chamber around the 20 combining nozzle into two compartments each with its own overflow valve, and to load the valve adjacent the delivery end of the combining nozzle by the pressure in the delivery chamber of the injector. Under 25 certain conditions, we have found that this construction will not enable the overflow to escape sufficiently freely to permit of the ready establishment of the condensed steam jet and the normal operation of the injector. 30 The difficulty of starting the injector is further accentuated by steam which may leak into the injector past the steam control valve or water which may leak into the injector past the delivery or back pressure valve, so 35 heating the feed pipe and causing an accumulation of hot water therein, so that the said water evaporates when the pressure on its surface is reduced by the action of the steam jet issuing into the combining nozzle 40 and the water is not readily lifted.

The object of our present invention is to provide improved means which insure the free escape of steam and water which may leak into the injector when it is not in use, 45 thus obviating the heating of the feed pipe and the feed water and enabling the injector to lift said water freely and to start promptly and also permit an increased overflow area until the jet is properly established 50 in the injector.

Referring to the accompanying explanatory drawings:

Figure 1 is a sectional elevation of an injector constructed in accordance with our invention.

Fig. 2 is a detail cross sectional view on the line A B of Fig. 1.

The injector comprises a steam inlet nozzle *a*, known as the lifting nozzle, and a central steam nozzle *a'*, known as the forcing nozzle, a water cone *b*, a combining nozzle divided into two parts *c*, *d* and a delivery nozzle *e*. Steam enters at *f* and water at *g*, the steam supply to the injector being controlled by a steam valve having a stem part *h* which enters within the forcing nozzle *a'*, and a part *i* which controls the admission of steam to the nozzle *a*. The valve *j* controls the admission of water to the injector.

The overflow chamber of the injector is divided into two compartments *k*, *m* delivering to a common overflow passage *n*. There are two overflow valves *o*, *p* for the said compartments, the one *p* being loaded by the pressure in the delivery chamber *g* by the plunger *r* and lever *s* as in our prior patents before referred to, while the valve *o* can be locked in its closed position for feed water heating purposes by the screwed spindle *t* as in Patent No. 1194207.

There is a water inlet valve *u* to the compartment *k* which works automatically according to the difference in the pressures at its opposite sides, but the water supply to the said valve may be cut off by the hand operated valve *v*.

Upon the overflow compartment *m* we provide a second overflow valve *w* held on its seat by gravity or a spring *x* but actuated by a cam *y* upon a spindle *z*. The latter carries a crank arm *3* which, by means of a connecting rod *4* is detachably attached to a projecting pin *5* on the arm *6* pivoted at *7* which actuates the steam valve.

With the arrangement before described, at starting, the lever *6* is operated to open the valve part *i*. The overflow valve *w* is then held off its seat by the cam *y* so that overflow can take place not only through the valves *o*, *p* but through the positively opened valve *w*. This greatly facilitates the starting of the injector. A further movement of the lever *6* opens also the valve portion *h* but it then allows of the closing of the valve *110*

w so that the overflow is then controlled entirely automatically by the pressure in the delivery chamber on the valve *p*.

The valve *w* is always fully open when 5 the steam valves *h*, *i* are closed so that any leakage past the said valve can escape freely to atmosphere.

If it is desired to preheat the feed water 10 the valves *o* and *p* are held closed by the locking spindle *t* and the connecting rod 4 is disconnected from the pin 5. When the steam valve is opened, the steam passes down the feed pipe and warms the feed water supply.

15 Having now described our invention what we claim as new and desire to secure by Letters Patent is:—

1. In injectors, in combination, lifting and forcing steam inlet nozzles, a combining 20 nozzle, a delivery nozzle, an overflow chamber divided into two compartments, each having communication with the interior of the combining nozzle, a delivery chamber, a steam control valve having portions controlling the steam supply to the lifting and the 25 forcing steam nozzles, a water inlet, automatic overflow valves upon each of said overflow compartments, a lever controlling one overflow valve and loaded by the pressure in 30 said delivery chamber, a positively operated overflow valve on the compartment having the lever loaded valve thereon, and means for opening said positive overflow valve when both the steam valve portions are shut or the lifting portion only is open, and insuring the closing of said overflow valve when both the steam valve portions are fully open, as set forth.

2. In injectors, in combination, lifting and 40 forcing steam inlet nozzles, a combining nozzle, a delivery nozzle, an overflow chamber divided into two compartments around the combining nozzle, a delivery chamber, a steam control valve having portions controlling the steam supply to both the lifting and the forcing steam nozzles, a water inlet, au- 45

tomatic overflow valves upon each of said overflow compartments, a lever controlling one overflow valve and loaded by the pressure in said delivery chamber, a positively operated overflow valve on the compartment having the lever loaded valve thereon, a lever operating the steam valve, a cam operating the positively actuated overflow valve and a connecting rod providing an operative connection between said valve lever and cam so as to open said positive overflow valve when both the steam valve portions are shut or the lifting portion only is open, and insuring the closing of said overflow valve 60 when both the steam valve portions are fully open, as set forth.

3. In injectors, in combination, lifting and forcing steam inlet nozzles, a combining nozzle, a delivery nozzle, a compartmentally divided overflow chamber, a water inlet, automatic overflow valves upon said overflow compartments, a delivery chamber, a lever controlling one overflow valve and loaded by the pressure in said delivery chamber, an extension piece attached to said lever and controlling the other overflow valve, a locking member for said extension piece, a water inlet to the overflow compartment adjacent the inlet end of the combining nozzle, means for positively cutting off said water inlet, a steam control valve having portions controlling the steam supply to both the lifting and the forcing steam nozzles, a positively operated overflow valve on the overflow compartment adjacent the delivery end of the combining nozzle, a lever operating the steam valve, a cam operating the positive overflow valve, and a connecting rod providing an operative connection between 85 said steam valve lever and cam, as set forth.

In testimony whereof we have signed our names to this specification.

JAMES METCALFE.

JAMES CROXON METCALFE.

RICHARD DAVID METCALFE.
